(No Model.)

D. DELANO.
TRUSS HOOP.

No. 437,645.

Patented Sept. 30, 1890.

UNITED STATES PATENT OFFICE.

DAVID DELANO, OF BALDWINSVILLE, NEW YORK, ASSIGNOR TO CATHERINE DELANO AND JOHN BOLEY, BOTH OF SAME PLACE.

TRUSS-HOOP.

SPECIFICATION forming part of Letters Patent No. 437,645, dated September 30, 1890.

Application filed July 19, 1889. Serial No. 317,972. (No model.)

To all whom it may concern:

Be it known that I, DAVID DELANO, a citizen of the United States, residing at Baldwinsville, in the county of Onondaga and State of New York, have invented certain new and useful Improvements in Truss-Hoops; and I do hereby declare the following to be a full, clear, and exact description of the invention, such as will enable others skilled in the art to which it appertains to make and use the same, reference being had to the accompanying drawings, in which—

Figure 1 is a plan view of my improved truss-hoop; Fig. 2, a vertical transverse section taken on line X X, Fig. 1; Fig. 3, an exterior edge view, and Figs. 4 and 5 are details.

Similar letters and figures of reference indicate corresponding parts throughout the several views.

My invention relates to that class of devices employed in coopering commonly termed "truss-hoops," and which in the process of manufacturing barrels, casks, &c., are placed around a barrel to strain the staves into proper position, compressing them circumferentially toward the chine, and thus leaving the bulge at the middle portion thereof.

In the commonly-used forms of the truss-hoops the jar, blows, and particularly the great outward strain or pressure to which they are subjected incident to the constructing of a barrel, tends to readily and quickly weaken and rupture the encircling truss-hoops, and consequently necessitating frequent renewals of same or new ones in lieu thereof at oft-recurring expense.

The object of my invention is to provide a truss-hoop combining comparative simplicity of construction and superior strength and durability and that will obviate the disadvantages and drawbacks connected with the ordinary forms of truss-hoops, thus furnishing a hoop that will prove efficient under severest usage, retaining unimpaired all essential operative and staying qualities for a lengthy period, and capable of being manufactured at small cost; and to that end my invention consists in securing to the top of the pressing-hoop an extra hoop for receiving the impingement of the cooper's tool, and thus

relieving the compressing-hoop from the wear and tear incident to the impingement of the aforesaid tool, all as hereinafter more fully described, and specifically set forth in the 55 claims.

1 represents my improved truss-hoop, which is composed of two stout flat hoops A A', of wood, each of which hoops is complete and self-sustaining. Said hoops are nearly or 60 quite of the same circumference externally, and are placed one upon the other. The lower hoop A, I designate the "compressing-hoop," inasmuch as its sole function is to press on the exterior of the staves during the operation of compressing circumferentially the 65 end of the barrel or cask in process of construction. The extra superimposed hoop A, I term the "pounding-hoop," for the reason that said hoop receives the impingement of 70 the cooper's tool in the process of tightening the hoop on the aforesaid barrel or cask, and thus the lower compressing-hoop is relieved from the wear and tear incident to the impingement of the cooper's tool in pounding 75 the truss-hoop down on the barrel or cask. The inner side of the pounding-hoop I bevel inward from the bottom to the top similar to the usual bevel of the subjacent compressing-hoop, and thus enlarge the top surface of the 80 pounding-hoop to afford more extensive and consequently more durable bearings for the pounding-tool. Said hoops are secured firmly together by rivets a, disposed at intervals circumferentially along their bodies and inserted vertically through both contracting 85 hoop-bodies and securely binding them together. Each of the hoops A A', I make complete and self-sustaining by forming the same with overlapping interlocking ends, as shown 90 at c in Figs. 2 and 3 of the drawings. This lock-joint connection of the meeting ends of the hoop portion A' is situated diametrically opposite that of the hoop portion A, whereby the joint of the pounding-hoop is sustained 95 by the solid central portion of the subjacent compressing-hoop, and, vice versa, the joint of the latter hoop is protected by the solid central portion of the top hoop, and thus the truss-hoop is so strengthened as to enable it 100 to effectually resist the strain incident to driving the same on the cask or barrel, and a far

greater degree of strength is imparted to the combined hoops than there would be were the meeting ends of the hoop portions A A' secured together at or about the same point.

5 C C are stays vertically encompassing at bottom, outer edge, and top of that portion of the truss-hoop whereat is formed the lock-joints c, through which pass vertical rivets d, that serve to bind or clamp the locked ends 10 of the respective hoop portions in close and unyielding embrace. Said stay C comprises a vertical edge portion and top and bottom horizontal portions, and may be formed of an integral piece of metal, as shown in Fig. 4 of 15 the drawings, or of independent parts connected to the hoop portions and to each other by rivets, as illustrated in Fig. 5 of the drawings.

Having described my invention, what I 20 claim as new, and desire to secure by Letters Patent, is—

1. The improved truss-hoop composed of a hoop for compressing the barrel circumferentially and an extra hoop secured to the top

of the compressing-hoop for receiving the impingement of the cooper's tool, substantially as set forth.

2. A truss-hoop composed of a compressing-hoop and a pounding-hoop secured to the top of said compressing-hoop and disposed with 30 the tied ends of one diametrically opposite the tied ends of the other, as set forth and shown.

3. A truss-hoop composed of a compressing-hoop and a pounding-hoop secured to the top 35 of said compressing-hoop, and each of said hoops formed with a lock-joint and disposed with said joint diametrically opposite that of the other hoop, substantially as described and shown.

In testimony whereof I affix my signature, in presence of two witnesses, this 11th day of July, 1889.

DAVID DELANO.
